UNITED STATES PATENT OFFICE.

HEINRICH KOPPERS, OF ESSEN-RUHR, GERMANY, ASSIGNOR TO THE KOPPERS DEVELOPMENT CORPORATION, A CORPORATION OF PENNSYLVANIA.

FRACTIONAL DISTILLATION PROCESS AND APPARATUS.

Application filed July 6, 1921, Serial No. 482,804, and in Germany April 22, 1918.

In processes for decomposing natural or artificial liquid mixtures, for instance, in the treatment of crude petroleum, or the distillation of brown coal or coal tar, the usual method is to transfer the quantity to be distilled at any one time, possibly fifty tons, to a vessel which is then suitably heated, after which the vapors are separated into fractions by means of cooling and reflux cooling. The different fractions are separated by either raising the temperature or subjecting them to a graduated vacuum, or by subjecting them to both the raised temperature and the graduated vacuum. This customary process may have the advantage of being so simple that it can be operated by ordinary workmen, but the preliminary treatment of a large quantity of the substance results in a number of objectionable features. On account of the lack of local uniformity in the supply of heat, no sharply defined separation of the fractions is obtained, and the liquid is or may be overheated and decomposed, which may also cause considerable wear and tear on the vessel. To this must be added the danger of local boiling which may easily occur particularly in connection with large quantities, and entails detrimental consequences in the way of violent over-boiling. The treatment of such large quantities by stepwise operation also involves the danger of fire and explosions. Attempts have been made to remove objectionable features of the stepwise process by subjecting these liquid mixtures to constant treatment by conducting them in an uninterrupted current through a number of vessels which are regulated, as regards their temperature and the pressure, for the expulsion of the different fractions, the latter being obtained in as many coolers by re-liquefying. However efficient such an uninterrupted process may be, both the arrangement and the operation become so complicated, that ordinary workmen are no longer capable and supervision by specially trained attendants becomes necessary. For that reason, this process has not been adopted to the extent which might have been expected on account of the above mentioned objectionable features of uninterrupted or continuous operation.

The present invention relates to a process and arrangement for the stepwise distillation of any desired liquid mixtures, combining the advantages of the present un-

interrupted operation and the constant distillation, while excluding the disadvantages, this being accomplished by conducting the quantity to be distilled at any time in a constant current through a single distillation apparatus, in which the distillation, with the aid of reflux cooling, is divided into two sharply separated fractions. In connection therewith, the residue of the first distilled charge, by properly regulating the temperature and the vacuum in this distillation apparatus and the reflux cooling, is again subjected to distillation and in this connection the distillation is again divided into two fractions. When in this manner by suitable repetition a complete distillation of the first quantity separated has been accomplished, a new liquid quantity is subjected to the same process. The arrangement suitably used for this process consists of the distillation apparatus proper and two receptacles which can be alternately connected in such a way that, during one operating stage, one of them contains the quantity to be distilled and the other one receives the resultant residue, while, by setting the apparatus for the second operating stage, the task of the two receptacles is reversed, the first one now receiving the residue remaining after the distillation and the second one containing the mixture to be distilled. In order to enable this residue and the two fractions obtained by liquefying to flow back freely, in view of the possibly greatly increased vacuum, the distillation device, the dephlegmating column with reflux cooler and the final cooler are placed at so high a point that a free flowing back into the low level storage or catching receptacles is rendered possible at any time.

In order to make the invention more clearly understood there is shown in the accompanying drawing means for carrying the same into practical effect, the invention not to be limited to the particular embodiment which is herein used for illustration and explanation. In said drawing is shown an elevation of an apparatus for stepwise distillation according to my invention.

The low receptacles, 10 and 11, are connected with each other by pipes 12 and 15 and may be, each respectively, connected, by means of the three-way cock 13, to the conduit 14 and by the three-way cock 16 to the pump 17, which latter, by way of a by-pass

18 and a regulating device 19 raises the liquid to the distilling device proper through conduit 20. Said device consists of the flat trays or pans 21 which are connected in series by the over-flow pipes 22 to provide a worm path in which a zig-zag route is also imposed on the liquid by means of ribs. The heating takes place in this connection by pipe coils 32 located in the liquid or cast into the bottom and operated with water under pressure. Through the conduits 23 the trays 21 are connected to the dephlegmating column 24 provided with reflux cooling means, from which a conduit 25 leads to the final cooler 26. From the column 24 a suction pipe 27 provided with siphon lock leads to the collecting receptacle 28 and from the final cooler 26 a similar conduit 29 to the collecting receptacle 30. Both the base of the dephlegmating column and the cooler above the same have coils 31 cast into the jacket through which steam or water flows in order to make it possible accurately to regulate the temperature in the lower and the upper parts, for the purpose of separating at any time two different liquids of given properties; in order to maintain the continuity of action automatic regulators can be applied. The dephlegmator as such is insulated since it is merely supposed to be a washing device.

The liquid quantity subjected to treatment at any time is filled into one of the receptacles for instance, 11, which is closed against conduits 12 and 14 by means of the cock 13, while connecting with the pump 17 through cock 16.

The liquid is conducted, in a quantity regulated per time unit by the by-pass 18, through the trays 21 where the temperature and pressure conditions are so adjusted that the group of ingredients boiling first is expelled. The reflux cooling for the dephlegmating column 24 is also adjusted with reference to these conditions so that a separation into two parts is obtained which reach the receptacles 28 and 30. The resultant residue of the distillation of the mixture in the receptacle 11 which remains during this first stage goes through conduits 14 and 12 into the receptacle 10. When the entire quantity which was contained in the receptacle 11 has been treated, the cocks 13 and 16 are reversed, while at the same time the temperature and pressure conditions in the distillation device 21 and the reflux cooling column 24 are regulated for the next fraction. In this manner, complete distillation of this originally divided quantity is possible under conditions which can be regulated and observed with accuracy, in which connection the apparatus can be operated without any difficulty and with perfect safety by ordinary workmen. Since only a comparatively small quantity is subjected to distillation at

any one time, all local inequalities which are unavoidable in heating large quantities can be obviated, which renders possible a sharp separation of the fractions and precludes the possibility of local over-heating with decomposition and deposits. The small quantity in conjunction with the constant movement of the liquid through the distillation device also does away with the local boiling and thus the over-boiling, and also a high degree of safety in regard to fire is attained. At the same time the exceptionally important structural advantage is obtained for the arrangement that the distilling trays can be made of cast iron to protect them against undue wear, which would be impossible in connection with a large vessel which is subjected alternately to heating and cooling and subject to a high vacuum. The manner of treatment described also permits of a further improvement: the raw material to be expelled frequently contains acids or salts; thus certain oils eliminate muriatic acid at high temperatures, while other oils or tars contain ammonium chloride. Now, so that corrosion or obstructions by salts may be avoided, a layer of carbonate of lime is arranged in uniform pieces in the vapor chamber of the dephlegmator, by which the acid is neutralized and salts like ammonium chloride are decomposed. It is also possible to insert in the oil cycle a special receptacle with carbonate of lime in order to suitably neutralize acid bodies or salts. The arrangement used for the process itself is exceedingly simple and withal inexpensive, both as regards the cost of installation and the operation, since the wear is very slight.

What is claimed is—

1. An apparatus for the stepwise distillation of natural or artificial liquid mixtures of ingredients which have different boiling points, having in combination: storage receptacles, a series of vaporizing devices connected thereto and arranged one above another, pressure means arranged to deliver a quantity of the liquid mixture from said storage receptacles to the uppermost of said vaporizing devices, and means for conducting the residue of said liquid mixture from the lowermost of said vaporizing devices to said storage receptacles, each of said vaporizing devices consisting of a flat cast iron tray through which the liquid flows in a thin layer, and provided with heating means.

2. A process for the stepwise distillation of natural or artificial liquid mixtures of ingredients which have different boiling points, for separating the ingredients at different boiling points, one group of ingredients at a time, which consists in: passing a quantity of such mixture in a constant current through a vaporizing device whose temperature and pressure conditions are regulated to distill the highest boiling point

ingredient of the group to be eliminated; are regulated to distill off a group of ingredients having different boiling points, said vaporizing device being regulated with reference to the highest boiling point in- 30
5 the remainder of the eliminated ingredients to a cooler whose temperature is regulated to take off the other fraction; discontinuing the elimination of such group of ingredients and regulating the temperature and pressure 35
10 conditions in the vaporizing device and regulating the temperature in the dephlegmator and in the final cooler for the elimination of another higher boiling point group; and then passing the remainder of said quantity 40
15 of said mixture through the same vaporizing device and passing the ingredients vaporized therein into the same dephlegmator and into the same cooler.
3. A process for the stepwise distillation 45
20 of natural or artificial liquid mixtures of ingredients which have different boiling points, for separating the ingredients at different boiling points, which consists in: passing a quantity of such mixture in a con-
25 stant current through a vaporizing device whose temperature and pressure conditions
